J. H. HALL.
SAFETY ELEVATOR CAR.
APPLICATION FILED DEC. 3, 1912.

1,073,898.

Patented Sept. 23, 1913.

UNITED STATES PATENT OFFICE.

JAMES H. HALL, OF BROOKLYN, NEW YORK.

SAFETY ELEVATOR-CAR.

1,073,898.

Specification of Letters Patent. Patented Sept. 23, 1913.

Application filed December 3, 1912. Serial No. 734,655.

To all whom it may concern:

Be it known that I, JAMES H. HALL, a citizen of the United States, and residing at Brooklyn, in the county of Kings and 5 State of New York, have invented certain new and useful Improvements in Safety Elevator-Cars, of which the following is a specification, such as will enable those skilled in the art to which it appertains to make 10 and use the same.

This invention relates to elevators, and the object thereof is to provide the car of a device or apparatus of this class having the usual suspending and operating cable 15 and the usual counterbalance weight or weights with a safety or locking apparatus or mechanism, whereby, if the operating cable or the support of the counterbalance weight or weights should break, the car 20 would be locked against downward movement, said apparatus also involving means whereby the car, if caught between floors or landings, can be lowered step by step by the operator thereof; and with this and other 25 objects in view the invention consists in a safety attachment or apparatus for elevator cars constructed and operating as hereinabove described.

The invention is fully disclosed in the 30 following specification of which the accompanying drawing forms a part, in which the separate parts of my invention are designated by suitable reference characters in each of the views, and in which;—

35 Figure 1 is a sectional side view showing the top portion of an elevator car provided with my improvement and two of the guide posts, and the construction at the top of said guide posts which also involves a part 40 of my improvement;—Fig. 2 a central vertical section on the line 2—2 of Fig. 1; Fig. 3 a sectional plan view on the line 3—3 of Fig. 2, with part of the construction broken away; and;—Fig. 4 a partial central vertical section on the line 4—4 of Fig. 2, but 45 showing the parts in a different position.

In Figs. 1 and 2 of the accompanying drawing I have shown at α the top part of a vertically movable elevator car which, in 50 practice, is mounted in an elevator shaft provided with the usual corner guide posts b only two of which are shown, and said guide posts are preferably L-shaped in cross section, and are connected at the top by a 55 strong rigid frame b^2 involving a top mem-

ber or members b^3 , a bottom member or members b^4 and side members b^5 . Mounted in the stationary top frame b^2 is a supplemental frame c involving a top portion c^2 and side portions c^3 , and said supplemental 60 frame is vertically movable to a slight extent in the main stationary frame b^2 and is supported by spiral springs c^4 , only one of which is shown, and placed between the bottom member b^4 of the main stationary 65 frame and the top portion c^2 of the supplemental frame. The supplemental frame c is provided at its opposite sides with suspended bolt engaging bars or members c^5 which are oblong in cross section and pro- 70 vided at regular intervals with oblong slots or openings c^6 between which are transverse members c^7 , and the bars c^5 extend downwardly to within a short distance of the bottom of the elevator well, and in the con- 75 struction shown, these bars pass downwardly inside of the opposite sides a^2 of the elevator car.

The top of the elevator car is provided with a raised yoke d having a central horizontal 80 part d^2 in which is formed a vertical chamber d^3 closed by top and bottom plates d^4 and d^5 which are securely bolted thereto, and movable vertically through the chamber d^3 and the top and bottom plates d^4 and d^5 85 thereof are rods d^6 and d^7 , and the suspending and operating cable d^8 is connected with one of said rods and the weight suspending cord or cable d^9 is connected with the other and provided with the usual counterbalance 90 weight or weights d^{10} . The rods d^6 and d^7 are provided at their lower ends with heads e which, in the construction shown, are rectangular in form and the lower end portions of said rods within the chamber d^3 are pro- 95 vided with collars or supports e^2 between which and the top closure plate d^4 of the chamber d^3 are placed strong spiral springs e^3 which normally serve to force said rods downwardly.

Mounted centrally on and vertically movable through the top a^3 of the car is a gear block j supported in a yoke-shaped device j^2 secured to the bottom of the top of the car and provided at its lower end with a pin j^3 movable through the head of the yoke-shaped device j^2 , and said block j is provided on its opposite sides with gear teeth j^4 which mesh with pinions j^5 and j^6 105 mounted in the hangers j^7 secured to the 110

top a^3 of the car, and pinions k and k^2 are supported above the top a^3 of the car by suitable uprights or bearings k^3 secured thereto.

The upper end of the gear block j is provided with a neck j^8 and mounted between the pinions k and k^2 is another gear block m the sides of which are provided with teeth which mesh with said pinions, and the gear block m , in the form of construction shown, 5 is provided with a downwardly directed neck m^2 which corresponds with and is adapted to bear on the neck j^8 of the gear block j , and placed between the gear blocks m and j is a strong spiral spring k^4 . The gear block m 10 is provided centrally of the top thereof with a rod m^3 which passes upwardly and is movable through the chamber d^3 and the top and bottom plates d^4 and d^5 thereof and also between the heads e of the rods d^6 and d^7 15 and the heads e of said rods are preferably recessed where the rod m^3 passes therebetween, as shown in Fig. 3.

Secured on the top a^3 of the car on the opposite sides of the center thereof are keepers n in which are placed lock bolts o movable transversely of the top of the car and the outer ends of which are adapted to operate in the slots or openings c^6 in the bars c^5 , and the inner ends of which are provided 20 with teeth o^2 which mesh with the teeth of the pinions k and k^2 . Secured on the under side of the top a^3 of the car are keepers p in which are mounted radially movable bolts r the outer ends of which are also adapted to 25 operate in the slots or openings c^6 in the bars c^5 , and the inner ends of which are provided with teeth r^2 which mesh with the pinions j^5 and j^6 , and the shaft of the pinion j^5 is provided with a downwardly directed 30 crank arm s adapted to be operated by the operator of the car, as hereinafter described.

The car suspending and operating cable d^8 is passed over the pulley t mounted in the stationary frame b^2 and may be connected 45 with and operated by any suitable mechanism as usual in apparatus of this class, and the weight suspending cord or cable d^9 is passed over pulleys t^2 mounted in the stationary frame b^2 .

50 The springs e^8 on the rods d^6 and d^7 are each stronger than the spring k^4 , and the normal position of the parts d^6 , e and m when the elevator is in operation is that shown in Fig. 4, and in this position of said 55 parts the bolts o are not projected, as shown in Fig. 2, and the main weight of the car is borne by the springs e^8 . If, in the operation of the car, the suspending and operating cable d^8 and the weight suspending cord or cable d^9 should break, both of the rods d^6 and d^7 would be forced downwardly into the 60 position shown in Fig. 2, and the bolts o would be projected into the position shown in said figure, and said bolts entering the 65 slots or openings c^6 in the bars c^5 would lock

the car against downward movement, as will be readily understood and the jar or jolt occasioned by thus stopping and locking the car would be broken or minimized by the downward movement of the supplemental frame c on the spring c^4 . If, in this operation, the car should be stopped between the floors or landings of a building, the operator thereof, by manipulating the crank arm s , could lower the car step by step in the following manner. When the arm s is thrown into the position shown in dotted lines, the bolts r would be projected and the bolts o withdrawn, and the car would drop one step, and then by swinging the arm s back into the position shown in full lines the bolts r would be withdrawn and the bolts o projected and the car would drop another step, and this operation could be repeated until the car has reached the desired position. 75

It will be understood that when the arm s is swung into the position shown in dotted lines the gear blocks j and m are both forced upwardly and the pinions j^5 and j^6 , and k and k^2 are all operated, and when the arm s 80 is moved back into the position shown in full lines the said gear blocks move downwardly and the said pinions move in the opposite direction.

It will also be understood that, if the operating cable d^8 alone should break the rod d^7 and its head e would be forced downwardly, as indicated in dotted lines in Fig. 4, and the result would be the same as though both the said cable and the weight 90 suspending cord or cable d^9 were to break; and if the said weight suspending cord or cable alone should break, the rod d^6 and its head e would be forced downwardly and the result would be the same as when the operating cable d^8 is broken. In other words the car will be locked as above described, and as shown in Fig. 2, if both the suspending and operating cable and the weight suspending cord or cable should break at the same time, 100 and the said car will be locked as shown in Fig. 2 if either the operating cable or the weight suspending cord and cable are broken separately. 110

My invention is not limited to the details 115 of the construction of the stationary top frame b^2 or its attachment, nor to the details of the construction of the supplemental vertically movable frame c mounted in said main frame, and these frames may be constructed in any desired manner and the main stationary frame b^2 may be supported in any preferred way, and changes in and modifications of these features of the construction, as well as other parts thereof, may 120 be made, within the scope of the appended claims, without departing from the spirit of my invention or sacrificing its advantages; and it will also be seen that the bars c^5 in connection with which the bolts o and r op- 125 130

erate, form in effect or operate as rack bars, and other forms of devices of this class may be employed.

Having fully described my invention, 5 what I claim as new and desire to secure by Letters Patent is:—

1. An elevator apparatus of the class described involving a vertically movable car, an operating cable and a counterbalance weight and cable connected therewith, vertical bolt engaging bars at the opposite sides of the car, transversely movable lock bolts mounted on the top of the car and adapted to engage said bars so as to lock the car 10 against downward movement, automatically operating devices for projecting said bolts into engagement with said bars on the breakage of either the operating cable or the counterbalance weight cable, and hand operated devices mounted in the top of the car and by means of which the lock bolts may be operated to lower the car step by step.

2. An elevator apparatus of the class described, involving a vertically movable car 25 mounted between guides, a stationary frame at the top of said guides, a vertically movable frame mounted in the stationary frame and supported by springs and provided with suspended bolt engaging bars which extend 30 downwardly at the sides of the elevator shaft, an operating cable connected with said car, a counterbalance weight and cable also connected with said car, transversely movable lock bolts mounted on the top of said car and adapted to operate in connection 35 with said bars, automatically operating devices adapted to move said bolts outwardly on the breakage of either the operating cable or the counterbalance weight 40 cable so as to lock said car against downward movement, and hand operated devices mounted in the top of the car and involving the said automatically operating devices, and by means of which the car may be lowered step by step.

3. In an elevator apparatus of the class described, a vertically movable car, vertical bolt engaging bars supported at the opposite sides thereof, transversely movable bolts 50 mounted on the top of the car and adapted

to operate in connection with said bars, devices for projecting said bolts on the breakage of the operating cable of the car so as to lock said car against downward movement, other transversely movable bolts mounted in the top of the car and also adapted to be operated in connection with said bars, and hand operated devices involving also the first named devices for operating said bolts so as to lower the car step by step. 55

4. In an elevator apparatus of the class described, a vertically movable car provided with a hoisting or operating cable and a counterbalance cable and weight, vertically movable rack bars supported at the opposite sides of the car, transversely movable bolts mounted in connection with the top of the car and adapted to operate in connection with said rack bars, devices for projecting said bolts on the breakage of the counterbalance weight cable to lock said car against downward movement, other transversely movable bolts mounted in the top of the car and also adapted to operate in connection with said bars, and hand operated devices 65 involving also the first named devices for operating said bolts so as to lower the car step by step. 70

5. In an elevator apparatus of the class described, a vertically movable car, bolt 80 engaging bars supported at the opposite sides thereof, transversely movable lock bolts mounted in connection with the top of the car and adapted to operate in connection with said bars, devices for projecting said lock bolts on the breakage of the operating cable of the car so as to lock said car against downward movement, and hand operated devices mounted within the car and also involving the first named devices for operating 85 said bolts so as to lower the car step by step. 90

In testimony that I claim the foregoing as my invention I have signed my name in presence of the subscribing witnesses this 2nd day of December 1912.

JAMES H. HALL.
